PAUL O. UNGER, OF SYRACUSE, NEW YORK, ASSIGNOR TO McMILLAN BOOK COMPANY,
OF SYRACUSE, NEW YORK, A CORPORATION OF NEW YORK

LOOSE-LEAF RECORD BOOK

Application filed December 27, 1927. Serial No. 242,741.

This invention relates to a new and improved loose leaf binder of the type usually called loose leaf record books.

In binders of this type hitherto known the binding posts have been individually pivotally mounted on pintles at their opposite ends. The result of this construction has been that it is a difficult matter to hold all of the posts in the same plane when it is desired to insert a new sheet in the binder.

Also binders of this character which have solid posts of necessity must always have the two covers a given spaced distance apart with the result that when there is in position in the binder a number of sheets less than the capacity of the binder they will not be firmly held in juxtaposition to each other and the book will be inconvenient to use.

Also when books of this character are used it is frequently necessary that a full complement of sheets be inserted in the binder or withdrawn therefrom and with the usual type of binder this is a difficult operation because it is hard to keep the holes in the sheets in alignment so that they may be passed readily over the posts.

The main object of my invention is to provide a binder in which the posts will be permanently held in the same plane irrespective of the movement of the posts with reference to the covers of the book.

Another object of my invention is to provide an adjustable fly leaf which will at all times hold in juxtaposition the sheets in the binder irrespective of the number of such sheets to prevent undue wear of the perforations of the sheets.

Another object of my invention is to provide co-acting supplemental fly leaves whereby a full set of sheets may be inserted in or withdrawn from the binder with rapidity and ease.

Another object is to provide in loose binders of this type, which are largely used for filing photographed record prints, an efficient means for compressing and thus straightening and flattening such prints, which, when fresh, are more or less crimped or warped.

Other objects and advantages relating to size, shape and arrangement of parts all as

will more fully appear from the following description taken in connection with the accompanying drawings in which:

Figure 1 is a perspective view of my binder in the open position and with the adjustable fly leaf inserted therein. 55

Figure 2 is a section partially broken away on line 2—2 of Figure 1 with the binder in the closed position.

Figure 3 is a section partially broken away on line 3—3 of Figure 2. 60

Figure 4 is a top plan view partially in section and partially broken away of the posts of my binder in locked position.

Figure 5 is a partial view similar to Figure 4 with the posts in the unlocked position. 65

Figure 6 is a section on line 6—6 of Figure 3.

Figure 7 is a perspective view of my supplemental fly leaves. 70

Figure 8 is a perspective view, partially broken away, of my binder and one of the supplemental fly leaves illustrating the way in which the fly leaves are used with the binder. 75

Figure 9 is a section on line 9—9 of Figure 7 with the supplemental fly leaves in closed position and with a set of leaves inserted therebetween.

My device consists of covers —1— and —2—, joined together by a flexible back —7—, formed of heavy cardboard or other appropriate material and preferably covered on the outside by a cover —3— of leather or other durable material, and also preferably covered on the inside by a cover —4— of an appropriate durable material. An end plate —5— is positioned on the inner end of cover —1— and is held in position by rivets —6— or other appropriate means. End plate —5— extends inwardly beyond the inner edge of cover —1— and is returned bent to form a cylindrical journal —8— for a purpose hereinafter to be described. Journal —8— is cut away, as shown at —9— on Figure 4, to receive the ends of the posts hereinafter to be described. 80

A second end plate —10— is positioned along the inner edge of cover —2— and is fastened therein by means of rivets —11—. 90

95

100

End plate —10— extends inwardly beyond the inner edge of cover —2— and is returned bent to form a housing —17— for a pintle-carrying member hereinafter to be described.

5 End plate —10— is cut away, as shown at —12— on Figure 5, to permit the insertion therein of posts hereinafter to be described.

Posts —13— are preferably formed of an unbendable material rectangular in cross section and having reduced ends —14— with holes —15— through each of the reduced ends —14—. A plurality of posts —13—, in this case shown as five, are rigidly secured by welding or other appropriate means to a 10 cylindrical rod —16— and are positioned so as to be always in the same plane irrespective of the rotation of rod —16—. Rod —16— is rotatably positioned in journal —8— of end plate —5— with the posts —13— positioned 15 through the cut-away portions —9— of housing —8—.

A pintle-carrying member —18— carrying a plurality, in this case shown as five, of pintles —19— is slidably positioned in housing —17— in such a manner that in one position the pintles —19— will extend across the openings —12— and in another position will be withdrawn from openings —12—. The posts —13— when the binder is in the closed 20 position, extend into openings —12— for the reception in holes —15— of pintles —19— for the purpose of locking the posts in position. Pintle-carrying member —18— has at one end a handle —20— by which it may be 25 moved back and forth in housing —17—. A lock —21— is positioned adjacent to pintle-carrying member —18—. Pintle-carrying member —18— has in the edge adjacent to lock —21— a slot —22— for the reception of 30 bolt —23— of lock —21—. When pintle-carrying member —18— is in position with pintles —19— in holes —15—, as shown in Figure 4, the bolt —23— will be in slot —22— and will prevent the retraction of pintle-carrying member —18—. When it is 35 desired to retract pintle-carrying member —18— a key, not shown, is inserted in lock —21— and bolt —23— is retracted and held 40 in the retracted position by a detent —24—, as shown in Figure 5, and pintle-carrying member —18— may then be retracted to remove pintles —19— from holes —15— thereby releasing posts —13—. When pintle-carrying member —18— is retracted to its 45 outward position the inner edge of slot —20— will contact with detent —24— which will release bolt —23—. Bolt —23— however, 50 can not enter slot —22— until pintle-carrying member —18— has again been pushed forward to bring slot —22— in registration with bolt —23—. When this is done bolt —23— will automatically enter slot —22— and lock pintle-carrying member —18— in 55 position.

Adjustable fly leaf —25— made of heavy canvas or other appropriate material and of approximately the same size and shape as cover —1—, carries at its inner edge a housing —26— secured thereto by rivets —27— or other appropriate means. Housing 70

—26— is provided with a plurality, in this case shown as five, of holes —28— to permit the passage therethrough of posts —13—.

A spring locking member —29— is positioned in housing —26— and consists of a metal strip —30— which carries on its end a spring —31—.

Spring —31— being so positioned that in the locked position it will extend into a hole —28— sufficiently far to press against a post —13— to hold fly leaf —25—

from movement on post —13—. Another strip —32— is positioned in the end of housing —26— opposite to that in which strip —30— is positioned and carries on its end

80 a similar spring —33— which in the locked position extends into another opening —28— sufficiently far to press against another post —13— to also prevent movement of fly leaf —25—.

Strips 85 30 and 32 are connected to a bell-crank —34— by means of links —35— and —36—. Bell-crank —34— is pivotally mounted on a pin

—37— which is positioned in housing —26— thereby forming a toggle joint between strips 90 —30— and —32—.

95 Springs —31— and —33— have their ends bent upwardly so that when fly leaf —25— is placed on posts —13— it may be pressed downwardly against the action of springs —31— and —33—.

100 The ends of springs —31— and —33— which bear against their respective posts —13— being bent upwardly will exert a pressure against such posts —13— when it is attempted to raise fly leaf —25—, and in order to raise fly leaf —25— it will be necessary to rotate bell-crank —34— which through links

—35— and —36— will retract strips —30— and —32— and will withdraw springs —31— and —33— from registration with their 105 respective posts —13—, and the fly leaf can 110 then be raised.

Supplemental fly leaves —38— consist of a bottom portion —39— and a top portion

115 —40— both constructed of a flexible heavy paper or other appropriate material and are of approximately the same size and shape as cover —1—.

Bottom portion —39— carries on its rear edge a plate —41— which is provided with a plurality of holes, in this case

120 five, —42— to permit the passage therethrough of posts —13—.

A plurality, in this case shown as four, of cylindrical posts —43— are rigidly positioned in plate —41— in spaced relation and are of an appropriate

125 height to extend through the full complement of leaves —44—, when my binder is filled to capacity.

Posts —43— are internally threaded on their upper end, as shown at —45— in Figure 9, for the reception of

screws —46— for a purpose hereinafter described. Top portion —40— carries on its rear edge a plate —47— which is provided with a plurality, in this case shown as five, of holes —48— to permit the passage therethrough of posts —13—. Plate —47— is also provided with a plurality, in this case shown as four, of cylindrical holes —49— to permit the passage therein of the upper ends 10 of posts —48—.

Operation

When it is desired to insert or withdraw sheets —44— from my binder, lock —21— will be unlocked and pintle-carrying member 15 —18— will be retracted thereby withdrawing pintles —19— from posts —13— and allowing cover —2— to be taken off posts —13—. Bell crank —34— will then be rotated to withdraw springs —31— and —33— from 20 contact with posts —13— and adjustable fly leaf —25— will be removed from posts —13—. Sheets —44—, it being understood that such sheets carry a plurality of holes —50— and 25 —51— to permit the passage therethrough of posts —13— and posts —43—, may then be placed in position on posts —13— or removed therefrom after which adjustable fly leaf —25— will be placed in position on posts 30 —13— on top of sheets —44— and pressed downwardly until it contacts with the upper one of sheets —44— to hold such sheets in juxtaposition. Cover —2— will then be replaced on posts —13— and pintle-carrying 35 member —18— pushed inwardly to lock cover —2— to posts —13—.

When it is desired to temporarily withdraw a full complement of sheets —44— from the binder, cover —2— will be removed from 40 posts —13— and adjustable fly leaf —25— also removed from posts —13— in the manner just described. Bottom portion —39— will then be placed on top of sheets —44— and posts —43— inserted through holes —51— and bottom portion —39— pressed downwardly until it contacts with the upper sheet 45 of sheets —44—. Bottom portion —39— carrying sheets —44— may then be lifted from posts —13—. Upper portion —40— will then be placed on the bottom one of sheets 50 —44— with posts —43— extending into holes —49— and screws —46— will then be placed in the threaded ends of posts —43— to lock bottom portion —39— and upper portion 55 —40— together.

When it is desired to replace a full complement of sheets in the binder, screws —46— are withdrawn from posts —43— and upper portion —40— removed. The binder being 60 open bottom portion —39— carrying sheets —44— may be placed on posts —13— and pressed downwardly until posts —13— register with holes —42—. Bottom portion —39— 65 may then be withdrawn from sheets —44—

and the binder again placed in the locked position in the manner heretofore described.

I claim:

1. In a device of the class described two opposed covers, a rod rotatably mounted in the edge of one cover, a plurality of posts each having one end rigidly secured to the rod and means for pivotally securing the other ends of said posts in the edge of the other cover.

2. In a device of the class described two opposed covers, a rod rotatably mounted in the edge of one cover, a plurality of posts each having one end rigidly secured to the rod, said posts being all in the same plane, and means for pivotally securing the opposite ends of the posts in the edge of the other cover.

3. In a device of the class described, two opposed covers, a plurality of posts secured together in a group pivotally mounted at the edge of one cover, and means for pivotally mounting the other cover to the other ends of the posts.

In witness whereof I have hereunto set my hand this nineteenth day of December, 1927.

PAUL O. UNGER.
